[57] CLAIM

The ornamental design for a CD rack, as shown and described.

DESCRIPTION

FIG. 1 is a front perspective view of a CD rack showing my new design;

FIG. 2 is a right side elevational view thereof;

FIG. 3 is a front elevational view thereof;

FIG. 4 is a rear elevational view thereof;

FIG. 5 is a top plan elevational view thereof;

FIG. 6 is a bottom plan view thereof; and,

FIG. 7 is a left side elevational view thereof.

The portions broken away in FIGS. 1-4 and 7 indicate an indeterminate length of cord and are for convenience of illustration.

FIG. 1

FIG. 2FIG. 3FIG. 4

FIG. 5

FIG. 6

FIG. 7
